UNITED STATES PATENT OFFICE.

EDWARD S. LEA, OF TRENTON, NEW JERSEY, ASSIGNOR, BY MESNE ASSIGNMENTS, TO ROBERT WOLSTENHOLME, OF PHILADELPHIA, PENNSYLVANIA.

MOTIVE POWER FOR AUTOMOBILES, &c.

No. 922,489.

Specification of Letters Patent.

Patented May 25, 1909.

Application filed November 9, 1907, Serial No. 401,429. Renewed December 17, 1908. Serial No. 468,082.

To all whom it may concern:

Be it known that I, EDWARD S. LEA, resident of the city of Trenton, county of Mercer, and State of New Jersey, have invented 5 an Improvement in Motive Power for Automobiles, &c., of which the following is a specification.

My invention has reference to motive power for automobiles, &c., and consists of 10 certain improvements which are fully set forth in the following specification, and shown in the accompanying drawings, which form a part thereof.

Heretofore, considerable difficulty has been 15 experienced in the use of automobiles employing gasoline engines as the motive power, owing to the fact that the water cooler in cold weather becomes frozen, if care is not exercised, with the result that the coolers are 20 frequently cracked and rendered unfit for use. This is especially the case where the automobile is employed in commercial business, and is under the control of a man of comparatively low order of intelligence, 25 whose neglect of the requirements under the special conditions of the weather frequently permits the water in the cooler to become frozen, resulting in damage which is both expensive and inconvenient to repair, to say 30 nothing of the loss of the use of the automobile during the period of repair.

The object of my invention is to overcome 35 the above objections by providing the explosive engine with a cooler and associated parts, whereby, should the engine remain at rest for a considerable length of time the cooler coils automatically, or otherwise, discharge themselves of their fluid contents and are thus rendered safe from the dangers of 40 freezing.

My invention consists of an explosive engine combined with one or more water coolers at a higher elevation than the engine, means for circulating the water from the engine 45 through the water coolers, and means for automatically draining the water coolers whenever the engine remains out of operation for a considerable period.

My invention further consists of one or 50 more coolers arranged out of the horizontal plane and having their highest and lowest parts connected with a receiving tank by tubular connections of different resistances to the flow of the water, combined with an 55 explosive engine receiving water from the

lower part of the tank, and a pump to circulate the water from the engine and tank and deliver it into the coolers at their lowest parts.

My invention also comprehends details of 60 construction which, together with the features above specified, will be better understood by reference to the drawings, in which:—

Figure 1 is a sectional elevation of an automobile cab containing motive apparatus embodying my improvements; Fig. 2 is a plan view of the top of the cab showing the coolers; and Fig. 3 is an elevation showing a modified form of my invention. 65

A is the cab of the automobile, and may be made in any suitable manner desired.

B is the roof of the cab, and located upon the said roof are the water coolers C C, the said coolers being preferably arranged at a 70 slight incline.

D is a water tank arranged within the cab, and may be provided with a gage glass N. The upper parts of the coolers C C are connected by a pipe I with the upper portion of 80 the tank D, so that the water flowing from the upper portions of these coolers may pass downward into the tank D. The water in the tank D is supplied by a pipe L to the jacketed cylinders of the engine E which 85 may be of any ordinary explosive type. This engine may be located within the cab or on any other part of the vehicle as preferred. The heated water from the engine is driven by a pump F upward through the 90 pipe G into a pipe H, which connects the lowest portions of the two coolers C C.

It will now be understood that when the engine is running, the water circulates, passing upward through pipe G, then dividing, 95 and passing through the two branches of the pipe H into the lower portions of the coolers C C. The water leaves the coolers C C at the upper portions thereof, and flows downward through the pipe I into the tank D, 100 and thence back by pipe L into the engine to be again circulated. The tank D should have a capacity sufficient to receive all of the water from the coolers C C, so that when the engine is in operation, the water is at 105 the level of the dotted line y—y in the tank, but when the engine is out of operation, said water rises to the level of the dotted line x—x.

In view of the fact that the pipe I is con- 110

nected with the upper ends of the coolers C C, it is evident that to drain the pipes C C, it would be essential that the water should flow backward through the pipes H, H, G, 5 thence through the pump F, engine E, pipe L and into the tank D. If the pump F was a high speed rotary pump, similar to a fan for the purpose of circulating without pressure, this return of the water might be accomplished 10 as the pump would not be tight, but where the pump operates in a positive manner, which would prevent the return of the water, it then becomes necessary to provide means for draining the coolers C C directly 15 into the tank, and for this purpose I provide a short circuit pipe J of smaller diameter which may be provided with a needle or other valve K. This valve K is always kept partly open in cold weather, so that the pipe 20 J becomes a bleed or constantly operating drain pipe between the supply and discharge sides of the coolers. As long as the pump is in operation, water will flow continuously through the coolers in volume and very 25 slowly and in relatively small quantities through the bleed pipe J directly into the tank D. This bleed or leak around the coolers will not impair their function to any material extent; but should the engine be allowed 30 to rest for a long period, the water in the coolers C C will flow by gravity downward through the pipes H and through the bleed pipe J directly into the tank D, air from said tank rising through the pipe I into 35 the highest points of the coolers and permitting free flow of the water therefrom. In this manner, the cooling water is automatically discharged from the coolers C C into the tank D which is within the cab, and thereby 40 protected against the intense cold to which the coolers are subjected. In mild weather, the valve K may be kept closed.

In Fig. 2, I have shown the connections of the pipe I with one end of each of the uppermost manifolds of the coolers, whereas the pipes H H are connected with the other or lowermost manifolds of the cooler at the opposite end, so that there is the same resistance to the flow of water throughout every 50 portion of the coolers.

In Fig. 1, I have shown the tank D as arranged at an elevation above the engine, and for receiving the water from the coolers before passing to the engine, but this may be varied, as indicated in Fig. 3, in which case, the receiving tank D is arranged at a lower elevation than the engine and the water is received by the engine directly from the coolers.

60 Referring to Fig. 3, the engine E directly receives the water from the coolers by the pipe I. The heated water from the engine E is discharged by a pipe L' into the tank D. The water in the tank D is lifted through the 65 pipe M by the pump F and discharged up-

ward through the pipes G, H, into the coolers C C. In this manner, the circulation is from the coolers by pipe I into the engine, and from the engine by pipe L' into the tank D. The water then passes by the action of 70 the pump upward through the pipes M, G, H, into the coolers. A short circuit pipe J' and a needle valve K' therein are provided between the pipes G and L' and correspond to the pipe J and valve K of Fig. 1, as in this 75 case they permit the water from the coolers to pass downward by pipes H and G through the pipe J' into the pipe L' and discharge into the tank D. A drain pipe I' having a valve i may connect the pipe I with the tank D for 80 the purpose of draining the engine when desired.

In these constructions above described, it is evident that the important feature of the invention resides in the means for properly 85 draining the coolers whenever the engine is brought to rest and maintained in that condition for any lengthy period, so that any carelessness or ignorance on the part of the man in charge can not destroy the operativeness 90 of the coolers, and thereby put the automobile as a whole out of service.

In my improvements herein set out, it is evident that the tank D must have capacity 95 to receive sufficient water from the coolers whereby they may be drained to such an extent as will prevent rupture from freezing; and while in practice, it is desirable that all the water shall be withdrawn, it is evident that this might not be essential in all cases. 100 For example, if instead of the coolers being placed on an incline, they were allowed to remain horizontal, or should the automobile be standing at an angle such as to bring either of the coolers C horizontal, then considerable 105 water might remain in the lower part of the cooler pipes notwithstanding the drainage connections, but this would provide an air space above the water and thereby prevent injurious results from freezing as the ice 110 would have space into which to expand. By supplying the water to the lowest parts of the coolers and discharging it from the highest parts, it is evident that in normal operation, the coolers are kept full of water, but under 115 these conditions it is not feasible to discharge automatically from the highest level parts of the coolers by a bleed line, and hence in the provision made this bleed line draws the water from the lowest part of the coolers 120 through the supply pipe connections, or otherwise, as found most satisfactory.

While this invention is specially designed 125 for use with gasoline operated trucks for commercial purposes, it is evident that it may be employed in stationary work or in connection with apparatus in which the gasoline engine is employed for operating hoisting machinery or other devices carried upon cars, boats, or other vehicles.

The pump may be of any construction found in the market, and such, for example, as is in use in connection with explosive engines, and I therefore do not restrict myself 5 to any character of pump.

The coolers C C may be of any construction desired, that shown being of the simple manifold form, and given as an example of a suitable cooler, for the purposes of illustrating 10 the objects and nature of my invention.

While I prefer the construction shown, the details thereof may be modified without departing from the spirit of the invention.

Having now described my invention, what 15 I claim as new, and desire to secure by Letters Patent, is:—

1. In a motive power adapted for automobiles, the combination of an explosive engine, a water tank for receiving the water to 20 be used to cool the engine, a water cooler at a higher elevation than the tank and engine, a discharge pipe from the cooler into the tank, a circulating pump for circulating the water from the tank through the engine and cooler, and a bleed pipe for discharging the water from the cooler into the tank without having to circulate through the cooler under 25 the action of the pump.

2. In a motive power adapted for automobiles, the combination of an explosive engine, a water tank for receiving the water to 30 be used to cool the engine, a water cooler at a higher elevation than the tank and engine, a discharge pipe from the cooler into the tank, a circulating pump for circulating the water from the tank through the engine and cooler, a bleed pipe for discharging the water from 35 the cooler into the tank without having to circulate through the cooler under the action of the pump, and a valve in said bleed pipe to control the flow of the water therethrough.

3. In a motive power adapted for automobiles, the combination of an explosive engine, a cooler for cooling the water used to 40 cool the engine arranged at a higher elevation than the engine, a tank having a capacity large enough to receive all of the water from the cooler and arranged at a lower elevation than the cooler, an overflow pipe from 45 the cooler into the tank, means for circulating the water contained in the tank through the engine and cooler, and a bleed pipe for permitting the flow of water from the supply side of the cooler to the discharge thereof, 50 whereby when the circulating means is at rest the cooler will automatically drain itself into the tank.

4. In a motive power adapted for automobiles, the combination of an explosive engine, a cooler for cooling the water used to 55 cool the engine arranged at a higher elevation than the engine, a tank having a capacity large enough to receive all of the water from the cooler and arranged at a lower elevation than the cooler, an overflow pipe 60

from the cooler into the tank, means for circulating the water from the tank through the engine and into the cooler, a bleed pipe for permitting the flow of water from the supply side of the cooler to the discharge thereof 70 whereby when the circulating means is at rest the cooler will automatically drain itself into the tank, and means to control the flow of water through the bleed pipe.

5. In a motive power adapted for automobiles, the combination of an explosive engine, a cooler for cooling the water used to cool the engine arranged obliquely and at a higher elevation than the engine, a tank having a capacity large enough to receive all of 80 the water from the cooler and arranged at a lower elevation than the cooler, an overflow pipe from the highest part of the cooler into the tank, means for circulating the water contained in the tank through the engine and 85 through the cooler by a port in the lowest part of the cooler, and a bleed pipe for permitting the flow of the water from the supply side and lowest part of the cooler to the discharge thereof whereby when the circulating 90 means is at rest the cooler will automatically drain itself into the tank.

6. In a motive power adapted for automobiles, the combination of an explosive engine, a water tank for receiving the water to 95 be used to cool the engine, a water cooler at a higher elevation than the tank and engine, a discharge pipe from the cooler into the tank, a circulating pump for circulating the water from the tank through the engine and cooler, 100 a bleed pipe for discharging the water from the cooler into the tank without having to circulate through the cooler under the action of the pump, and a cab inclosing the tank pump and pipe connections and arranged beneath and supporting the cooler.

7. In a motive power adapted for automobiles, the combination of an explosive engine, a cooler for cooling the water used to cool the engine arranged at a higher elevation than the engine, a tank having a capacity large enough to receive all of the water from the cooler and arranged at a lower elevation than the cooler, an overflow pipe from the cooler into the tank, means for circulating the water from the tank through the engine and into the cooler, a bleed pipe for permitting the flow of water from the supply side of the cooler to the discharge thereof 115 whereby when the circulating means is at rest the cooler will automatically drain itself into the tank, and a cab inclosing the tank 120 explosive engine and pipe connections and supporting the cooler upon the roof thereof.

8. In a motive power adapted for automobiles, a cab forming an inclosed space, a cooler secured upon the outside thereof, a tank arranged within the cab, a discharge pipe from the discharge end of the cooler into the tank, an explosive engine, means to cause 125 130

the water to circulate through the tank and explosive engine and supply it to the receiving end of the cooler, and a bleed pipe constantly open for transferring the water from 5 the cooler into the tank when the circulating means is at rest.

9. In a motive power adapted for automobiles, the combination of an explosive engine, a water tank for receiving the water to 10 be used to cool the engine, a water cooler at a higher elevation than the tank and engine, a discharge pipe from the cooler into the tank, and means for circulating the water through 15 the engine and cooler when the engine is in operation and draining the cooler into the tank when the engine is at rest.

10. In a motive power adapted for automobiles, the combination of an explosive engine, a cooler for cooling the water used to 20 cool the engine arranged at a higher elevation than the engine, a tank having a capacity large enough to receive all of the water from the cooler and arranged at a lower elevation than the cooler, an overflow pipe 25 from the cooler into the tank, means for circulating the water contained in the tank through the engine and cooler, and a pipe which will permit the flow of water from the supply side of the cooler to the tank, where- 30 by when the circulating means is at rest the cooler will automatically drain itself into the tank.

11. In a motive power adapted for automobiles, the combination of an explosive engine, a cooler for cooling the water used to 35 cool the engine arranged at a higher elevation than the engine, a tank having a capacity large enough to receive all of the water from the cooler and arranged at a lower 40 elevation than the cooler, an overflow pipe from the cooler into the tank, means for circulating the water from the tank through the engine and into the cooler, and means for guiding the flow of water from the tank to the 45 supply side of the cooler, and means for delivering water from the cooler to the tank whereby when the circulating means is at rest the cooler will automatically drain itself into the tank.

50 12. In a motive power adapted for automobiles, the combination of an explosive engine, a liquid tight cooler for cooling the water used to cool the engine arranged obliquely and at a higher elevation than the engine, a tank having a capacity larger than the capacity of the cooler, means to normally drain the water from the cooler into the tank when the engine is at rest, and means for forcing the water from the tank 55 through the cooler when the engine is in motion.

13. In a motive power adapted for auto-

mobiles, a cab forming an inclosed space, a liquid tight cooler secured upon the outside thereof, a tank arranged within the cab, a 65 discharge pipe from the discharge end of the cooler into the tank, an explosive engine, means to cause the water to circulate through the tank and explosive engine and supply it to the receiving end of the cooler, 70 and suitable pipes for transferring the water from the supply end of the cooler into the tank when the circulating means is at rest.

14. In a motive power adapted for automobiles, the combination of the engine, a liquid tight cooler for the engine, and automatically operated means for circulating a continuous body of water through the cooler and engine, and a constantly open drain pipe for discharging the water from the cooler to 80 empty it when the circulating means is out of action, and having a normal discharging capacity which is greatly less than the capacity of the automatically operated means for 85 circulating the water, whereby an excess of water is circulated by the automatically operated means over that which could pass through the drain pipe.

15. In a motive power adapted for automobiles, the combination of an engine, a liquid tight cooler for the engine, a tank at a lower level than the cooler and having a capacity greater than the cooler to receive substantially all the water from the cooler, means to circulate the water from the engine 95 through the cooler in one direction, and means for causing the water to flow through and from the cooler in the other direction and into the tank, whereby the cooler may be drained when the engine is at rest.

16. In a motive power, the combination of an explosive engine, a liquid tight cooler for the water from said engine, means for circulating the water from the engine in a solid body through the cooler, a receiving tank into which the cooler may be drained, and independent means for draining the water of the cooler into the tank.

17. In a motive power, the combination of an explosive engine, an inclosed cab surrounding the engine, a cooler for the water from said engine outside of the cab, means for circulating the water from the engine through the cooler, a receiving tank within the cab of greater capacity than the cooler into which the cooler may be drained, and means for draining the water of the cooler into the tank.

In testimony of which invention, I have hereunto set my hand.

EDWARD S. LEA.
